Application filed November 23, 1926. Serial No. 19,819. Term of patent 14 years.

To all whom it may concern:

Be it known that I, HENRY E. HENRICKS, a citizen of the United States, residing at Beaver, county of Beaver, and State of Pennsylvania, have invented a new, original, and ornamental Design for Bathtubs, of which the following is a specification, reference being had to the accompanying drawings, forming a part hereof.

In the drawings, Figure 1 is a perspective view of the bathtub showing my new design; and

Figure 2 is an end elevation of the tub.

The dominant feature of the design is the front face which is in the form of a substantially unbroken plane surmounted by a roll rim which extends out over the plane face.

I claim:

The ornamental design for a bathtub, as shown and described.

In testimony whereof I have hereunto set my hand.

HENRY E. HENRICKS.
